BLOTTER ATTACHMENT FOR PENS

George J. Schratz and William H. Funk,
Pittsburgh, Pa.

Application June 20, 1940, Serial No. 341,472

10 Claims.

(Cl. 120—26)

This invention relates to pens such as fountain pens and other types of ink-using pens, and is more particularly concerned with a blotter attachment for such pens.

5 In connection with ink-using pens, the question of drying the ink has always been somewhat of a problem. For a long time sand or other dry granules were employed for this purpose, but, of course, such was at best a temporary and inconvenient expedient. Moreover, such practice, while perhaps satisfactory for old fashioned pens, is not at all suitable for use with modern pens such as fountain pens. The common cellulosic blotter is, of course, very extensively employed today, 10 and while this is satisfactory, it nevertheless requires the provision of separate blotters, with the result that in many cases and under numerous circumstances such a blotter is not handy or available. It would be a matter of great utility 15 were the pens themselves provided with some sort of a blotter, but insofar as we are aware nothing has been done along this line commercially. While there have, we believe, been certain proposals in the past with relation to this subject, 20 so far as we are aware no one has produced a simple inexpensive blotter attachment which is effective and efficient and which has been commercially adopted.

It is, accordingly, one of the objects of this 30 invention to provide a blotter attachment for pens which, forming an integral part of such pens, is always at hand available for use.

Another object of the invention resides in the provision of an integral blotter attachment for 35 pens which is composed of a baked and molded clayey or ceramic material having a highly bulbulous character.

A further object of the invention resides in the provision of a blotter attachment for pens which 40 forms an integral part of the pen structure but which is removable and renewable when so required.

A still further object of the invention resides in so modifying the structure of a pen as to enable 45 the blotter attachment of the present invention to be detachably locked to such pen by means of an extremely simple joint and at a cost which is comparatively insignificant.

Other and further objects and advantages will 50 be understood by those skilled in this art or will be apparent or pointed out hereinafter.

In the accompanying drawing wherein we have 55 illustrated a number of forms of the present invention:

55 Figure 1 illustrates, partly in elevation and

partly in section, a conventional fountain pen provided with our new invention;

Fig. 2 is a view similar to Fig. 1 but illustrating the application of the present invention to the usual non-fountain type of pen; 5

Fig. 3 illustrates the application of the invention to a streamlined fountain pen such as that used in connection with a desk set;

Fig. 4 is an enlarged fragmentary view of a modification generally similar to the upper end 10 of Fig. 1 and illustrating in greater detail the operative relationship of the parts and further showing an attachment which is, in part, formed or molded with the pen at the time of manufacture thereof; and 15

Fig. 5 is a sectional view taken along the line V—V of Fig. 4.

Similar numerals designate corresponding parts throughout the various views.

Referring first to the form of the invention illustrated in Fig. 1, it is pointed out that this structural embodiment is adapted for application to fountain pens already manufactured in direct contrast to Fig. 4, as will be more fully appreciated hereinafter. The fountain pen of Fig. 1, 20 25 designated as a whole by the numeral 10, is generally composed of some non-metallic composition which may for convenience and brevity herein be termed a plastic or moldable material.

In applying our present invention to such a 30 pen we form an aperture 11 in the closed end of the conventional cap of the pen and in that aperture we insert a disc-shaped member 12 which, while preferably composed of metal, may be made of any suitable metallic or non-metallic material. 35 and may in particular be composed of a plastic or moldable material. This disc 12 is countersunk within the closed end of the cap. It is desirable that a snug fit be produced, and this may be secured in any well-known manner. Where 40 both fountain pen cap and disc are made of plastic material they may be united chemically or by heat in known manner, i. e., by means of a solvent or fused by heat.

This disc 12 has a short cylindrical shaft-like 45 extension 13 projecting at right angles therefrom. This shaft-like member is preferably made of the same material as the disc 12. The shaft-like member may, as stated, be cylindrical, i. e., of uniform diameter or cross-section throughout, al- 50 though we may make it slightly tapering toward its smaller or distal end. Intermediate its ends the shaft-like member 13 is provided with a circumferential groove or annular recess 14 and in this is disposed a split ring 15, preferably com- 55

posed of spring wire and of the nature of substantially a single convolution of a helical spring. The spring is of such nature that it always tends to expand outwardly. The spring is free to rotate in the groove and forms the center of rotation for the bulbous member. In effect, therefore, the spring also acts as a freely rotatable bearing.

In the form shown in Fig. 1, the blotter material is a tapered cylinder 16 which is composed of a baked and molded clayey material, i. e., a material such as is used for making ceramic ware. This material as molded and fired is hard and permanent in its character; it is characterized by extremely high bulbous capacity, being made up as it is of a vast number of capillary passages which extend throughout the material. The blotter attachment is therefore characterized by a very large ability to absorb moisture. The member 16 is provided with a tapering recess 17 as will be clear from the drawing.

Experiments have demonstrated that it is almost impossible to saturate a blotter of this character even when a very considerable amount of fresh wet ink is directly dropped on the blotter as by causing it to be discharged from a fountain pen. Eventually, of course, the blotter will become saturated or nearly saturated but this will not ordinarily occur except after a very considerable period of time. When this does happen, the blotter is replaced and the old one thrown away, the cost being so nominal as to make it unnecessary and undesirable to reclaim the same, although this can be done, if desired, by cleansing in water or a solvent and then drying at a mild heat. Thus it will be apparent that the blotter element 16 is removable and renewable.

It will be noted from Fig. 1 in particular that assembly and disassembly are readily accomplished with a minimum of manual operation. To disassemble, the blotter member 16 is drawn away from the cap in the axial direction thereof, the amount of force being inconsiderable and when applied serving to cause member 16 to compress the spring element 15 so as to enable the member to be readily removed. After removal, the spring expands, as will be appreciated from what has preceded, but in no case becomes disassociated from the groove 14 in the shaft-like member 13.

In applying a new attachment, the reverse operations are carried out, viz., the fresh member is placed over the shaft-like member and forced toward the cap. When the same encounters the spring it compresses the same, enabling the member to assume ultimately the position shown in Fig. 1 of the drawing, under which conditions the member 16 abuts the annular portion of the cap surrounding the said disc and the shaft-like member extends fully into the recess 17. When the member is fully applied, the spring expands to the maximum amount of which it is capable under the circumstances and grips the sides of the recess 17, thus serving to hold member 16 in position against accidental disassembly. The tapered nature of the recess 17 causes the distal end of the member 13 to wedge itself somewhat in the bottom of the recess, thus also tending to retain the parts in the desired state of assembly.

In Fig. 2 the modified form of our invention there illustrated comprises a blotter attachment 16a composed of the same material as that of Fig. 1. It will be noted from Fig. 2 that the

configuration of the attachment is considerably different, the intention being that a form be employed which will more suitably conform to the shape and type of the desk pen 10a. This is a non-fountain type of pen. With this in mind, it will be apparent that the attachment 16a is somewhat cigar-shaped, being tapered and rounded at either end, thus also avoiding the use of sharp corners or edges which might catch or break off. Otherwise, the modification is substantially that of Fig. 1, as is indicated by the use of similar numerals except that the groove 14a and ring 15a are provided on the end of the pen itself rather than on a separate or integral member.

In Fig. 3 a familiar type of pen 10b is illustrated such as is commonly employed as a part of what is known as a desk set, the pen having a long slender tapering frusto-conical end 13b. In this case the blotter attachment 16b is contoured more or less to correspond, the principle involved being similar to that of Fig. 2, as will be readily appreciated. As in Fig. 2, the groove 14b and spring 15b of Fig. 3 are formed in the end of the pen itself, and to this extent Figs. 2 and 3 represent very similar forms of the invention but apply to different types of pens to illustrate the applicability and versatility of the invention.

The forms of the invention illustrated in Figs. 1 to 3, inclusive, are primarily intended for application to pens already produced and on sale or in use. This is not, however, a restriction upon the invention since it is clearly apparent that the blotter attachment in accordance with those figures may be produced and applied to the pens prior to sale even though already manufactured. It is, however, within the purview of this invention to constitute the shaft-like mounting as a unitary part of a pen forming a part thereof at the time of manufacture or production. In other words, the shaft-like extension 13 and the disc portion 12 of Fig. 1 may be unitary with the cap of the pen, and may be initially so made. For example, if the pen cap 18 of Fig. 4 is made up of a plastic or non-metallic composition or material, the disc-like portion 12c (not now a distinct element) and the shaft-like extension 13c are made of that same material as is indicated by the continuous cross hatching in Fig. 4. The structure illustrated in this figure, while basically the same as in Fig. 1, is helpful in an understanding as to the mode of operation and the relationship of the parts due to the fact that the larger scale employed in Fig. 4 makes clearer illustration possible. The tapering recess 17c in the blotter attachment 16c of Fig. 4 shows up more clearly as does the wedging of the distal end of the shaft-like extension 13c in the bottom of such recess. Similarly, the difference in tapering clearly reveals the existence of a tapering annular space 17c around the extension. Otherwise the blotter attachment 16c is identical with that of Fig. 1 already described. From Fig. 5 the third dimension of the parts involved will become more clearly apparent, and while the same has been shown as circular such is for illustrative purposes.

Within the principles and scope hereof we may make various additions, omissions, substitutions and modifications besides those referred to above. Rather the invention is to be defined by the appended claims. While we have particularly described the blotter attachment as being composed

of a bibulous ceramic material, we do not intend to be limited solely thereto as other bibulous materials of a clayey or similar nature may also be employed. We do not intend, however, that cellulose materials shall constitute any part of this invention, in which term we include unsized papers such as blotting papers and the like. The pen itself may, of course, be of any known shape or material such as rubber, plastic, metal, etc., and the only effect of such upon our invention is a corresponding change in material where the invention is a unitary part of the pen and a change in configuration to conform to or harmonize suitably with the shape of the particular pen. Our invention involves the shaft-like extension either integral or unitary in combination with a bibulous ceramic blotter attachment which is mounted so as to permit of ready rotation, assembly and disassembly.

Having thus described my invention, what we claim as new and desire to secure by Letters Patent is:

1. A pen which is provided with a circular terminal portion having a circumferential groove near its extremity, a spring in said groove capable of expansion and contraction, an inorganic bibulous blotter element adapted to be detachably secured to the circular pen portion aforesaid and having a tapering recess within which the said extremity is adapted to be received, the said spring contracting during axial movement of said blotter element but otherwise expanding to grip the interior of said recess, the said blotter element and spring together forming a unit capable of rotation.

2. A fountain pen the cap member of which is provided with an axial shaft-like extension having a circumferential groove intermediate the ends thereof and a single coil spring located in said groove, a bibulous ceramic element characterized by great absorptive capacity rotatably mounted on said shaft-like extension, the said bibulous member being provided with an axial tapered recess adapted to receive said shaft-like extension in such manner that the distal end of such extension wedges itself in the smaller end of said recess and the said spring expands to grip the interior surface of the said bibulous member.

3. In combination with a pen having a circular portion provided with a circumferential groove and a single coil spring located in said groove, a bibulous ceramic member rotatably attached to the said pen and removably and removably mounted thereon, the said pen extending into a suitably configured recess formed in the said bibulous member to effect a wedging action and in such manner as to make the said spring rotate with the said bibulous member.

4. A pen which is provided with a circular terminal portion having a circumferential groove near its extremity, a spring in said groove capable of expansion and contraction, an inorganic bibulous blotter element adapted to be detachably secured to the circular pen portion aforesaid and having a tapering recess within which the said extremity is adapted to be received, the said spring contracting during axial movement of said blotter element but otherwise expanding to grip the interior of said recess, the said blotter element and spring together forming a unit capable of rotation, the pen and blotter element being so configurated as to constitue definite parts of a particular design motif.

5. A pen which is provided with a circular ter-

5 minal portion having a circumferential groove near its extremity, a spring in said groove capable of expansion and contraction, an inorganic bibulous blotter element adapted to be detachably secured to the circular pen portion aforesaid and having a tapering recess within which the said extremity is adapted to be received, the said spring contracting during axial movement of said blotter element but otherwise expanding to grip the interior of said recess, the said blotter element and spring together forming a unit capable of rotation, the blotter element being in the form of a tapering cylinder.

6. A pen which is provided with a circular terminal portion having a circumferential groove near its extremity, a spring in said groove capable of expansion and contraction, an inorganic bibulous blotter element adapted to be detachably secured to the circular pen portion aforesaid and having a tapering recess within which the said extremity is adapted to be received, the said spring contracting during axial movement of said blotter element but otherwise expanding to grip the interior of said recess, the said blotter element and spring together forming a unit capable of rotation, the blotter element being of elliptical form.

7. A pen which is provided with a circular terminal portion having a circumferential groove near its extremity, a spring in said groove capable of expansion and contraction, an inorganic bibulous blotter element adapted to be detachably secured to the circular pen portion aforesaid and having a tapering recess within which the said extremity is adapted to be received, the said spring contracting during axial movement of said blotter element but otherwise expanding to grip the interior of said recess, the said blotter element and spring together forming a unit capable of rotation, the blotter element being in the form of an elongated cone.

8. A pen which is provided with a circular terminal portion having a circumferential groove near its extremity, a spring in said groove capable of expansion and contraction, an inorganic bibulous blotter element adapted to be detachably secured to the circular pen portion aforesaid and having a tapering recess within which the said extremity is adapted to be received, the said spring contracting during axial movement of said blotter element but otherwise expanding to grip the interior of said recess, the said blotter element and spring together forming a unit capable of rotation, the circular terminal portion being an integral part of the pen.

9. A pen which is provided with a circular terminal portion having a circumferential groove near its extremity, a spring in said groove capable of expansion and contraction, an inorganic bibulous blotter element adapted to be detachably secured to the circular pen portion aforesaid and having a tapering recess within which the said extremity is adapted to be received, the said spring contracting during axial movement of said blotter element but otherwise expanding to grip the interior of said recess, the said blotter element and spring together forming a unit capable of rotation, the circular terminal portion being a unitary part of the pen.

10. A fountain pen the cap member of which is provided with an axial shaft-like extension having a circumferential groove intermediate the ends thereof and a single coil spring located in said groove, a bibulous ceramic element characterized by great absorptive capacity rotatably mounted on said shaft-like extension, the said bibulous

member being provided with an axial tapered recess adapted to receive said shaft-like extension in such manner that the distal end of such extension wedges itself in the smaller end of said recess and the said spring expands to grip the interior surface of the said bulbous member, the

shaft-like extension having a terminal disc which is set into the otherwise closed end of the said cap member.
